JOHN T. LANCASTER, OF NEWTON, MASSACHUSETTS, ASSIGNOR TO UNITED SHOE MACHINERY CORPORATION, OF PATERSON, NEW JERSEY, A CORPORATION OF NEW JERSEY.

PULLING-OVER MACHINE.

Application filed December 23, 1925. Serial No. 77,276.

This invention relates to machines for use in the manufacture of boots and shoes for shaping uppers over lasts, and in some of its novel aspects has more particular reference 5 to machines comprising in their organization means for pulling the upper over the last. The invention aims to provide improvements in means for performing various operations upon the work, including upper-pulling, wiping and fastening operations, and in a more general aspect has in view the provision of a simple, compact and convenient arrangement of mechanisms for performing the different operations.

15 In accordance with one important feature of the invention novel means is provided for wiping the upper heightwise of the last, an operation frequently hereinafter termed the upwiping of the upper. The machine herein 20 shown is provided with wipers for engaging the upper in spaced locations at the end of the toe and at the opposite sides of the forepart respectively and for wiping the upper toward the edge of the last bottom while it is held 25 under tension by the pulling means. This serves to supplement the action of the pulling means by further tightening the upper over the last, and also to smooth the upper adjacent to the edge of the last bottom in preparation 30 for the laying of its margin inwardly over the sole or insole. In the construction herein illustrated the several wipers are conveniently mounted on a single wiper carrier which is moved to effect the upwiping operation, and 35 are moved relatively to the wiper carrier into and out of engagement with the shoe. The invention further provides a novel arrangement of means for upwiping the upper and for wiping its margin inwardly over the bottom 40 of the last (herein termed the overwiping operation), the construction shown comprising an overwiping wiper adjacent to each of the upwiping wipers and operated through a "lost motion" connection by the same means 45 which moves the upwiping wiper into engagement with the shoe.

For pulling the upper over the last the invention provides novel gripper-operating means so constructed as to insure that the upper will be subjected to a predetermined tension without danger of an excess of tension such as might damage the upper. For the purpose in view the construction herein shown comprises, for operating each gripper,

a friction clutch which is automatically controlled in such manner as to subject the upper to a definite degree of tension determined adjustably by the pressure with which the co-operating clutch members are held yieldingly in engagement with each other, and then to 55 slip in response to resistance of the upper while holding it under the predetermined tension. Preferably also, as herein illustrated, the co-operating clutch members are provided with serrated interengaging faces for 60 subjecting the upper, in the relative slipping movement of the members, to repeated supplemental pulling impulses whereby the upper 65 is stretched more effectively to the required degree than by a single steady pull. 70 For greater precision in regulating the force of the pull each clutch is connected directly and positively to its gripper. The machine herein shown comprises grippers for pulling the upper respectively at the toe end and at 75 the opposite sides of the forepart of the last, and has a single spring control for both the side gripper clutches so as to equalize substantially the forces applied in pulling the upper 80 at the opposite sides.

For fastening the upper in pulled-over position the machine herein shown comprises mechanisms, including tack holders and drivers, for driving tacks or equivalent fastenings at the end and the sides of the forepart; and a 85 further feature of the invention consists in novel means whereby delivery of tacks to the tack holders is facilitated. While this feature of the invention does not depend for utility upon the driving of the tacks in any particular direction, it is especially useful in an organization such as herein shown in which the work is so positioned that the tacks are driven in substantially horizontal directions, since in an organization of that type there are 90 difficulties in the way of delivering tacks to the tack holders by gravity in the customary manner. For the purposes in view the invention provides for moving a tack holder into a position at a substantial angle to the line of 95 drive to receive a tack, the tack holders in the machine herein shown being turned from substantially horizontal driving positions into substantially vertical positions to receive tacks delivered from above through their outlet ends. The invention further provides a 100 convenient organization of mechanism for moving each tack holder between its different 105

positions, the construction shown comprising means whereby each tack holder and the corresponding tack driver are turned as a unit into and out of tack-receiving position in response to movement of a driver bar which operates the driver to drive the tack.

In addition to the above-mentioned features, the invention also provides a novel and convenient arrangement of operating instrumentalities, including separate toe and side grippers and upper-fastening mechanism positioned between the side grippers, a novel shoe rest construction, and other novel details and combinations of parts, all of which will be more particularly described by reference to the accompanying drawings and pointed out in the claims.

In the drawings,

Fig. 1 is a view in front elevation of the head portion of a machine in which the invention is embodied, parts of the structure being broken away and parts shown in vertical section;

Fig. 2 is a view of the head of the machine, partly in side elevation and partly in vertical section;

Fig. 3 is a plan view, with parts in horizontal section and parts broken away;

Fig. 4 is a vertical, sectional view, on a larger scale, of a portion of the structure shown in Fig. 2;

Fig. 5 shows, partly in side elevation and partly in section, one of the side tacking mechanisms;

Fig. 6 is a view in side elevation of the toe tacking mechanism;

Fig. 7 is a section on the line VII—VII of Fig. 1, showing the means for controlling the operation of the machine;

Fig. 8 is a sectional view, illustrating the character of means provided for inverting the tacks;

Fig. 9 is a section on the line IX—IX of Fig. 3, illustrating the character of the clutch through which operative movement of the toe gripper is effected; and

Figs. 10 and 11 illustrate different steps in the operation of the machine.

While the invention, in various novel aspects, is not limited as to the manner in which the shoe is positioned relatively to the operator of the machine, the machine herein shown is so constructed as to operate upon a shoe positioned with the bottom of its forepart in a substantially vertical plane and its toe pointing upward in a substantially vertical direction, so that the top of the forepart of the upper is presented conveniently in view of the operator as he stands in front of the machine. For thus positioning the shoe, in the construction shown, there is secured upon the frame of the machine a bracket 20 having thereon a vertical arm 22 in the upper end of which are mounted for horizontal movements a pair of slides 24 arranged to

serve as rests for the toe end of the insole on the last, the outer ends of these slides having thereon forwardly extending projections arranged to overlap the edge of the insole and thus to assist in centralizing the shoe both lengthwise and laterally. The slides 24 are provided with rack teeth arranged to engage respectively the opposite sides of a pinion 26 which is formed on a shaft 28 mounted in bearings in the arm 22, this shaft having on its lower end a knurled head 30 by which it may be turned to adjust the slides 24 simultaneously toward or from each other for different widths of shoes. Secured to the shaft 28 are a pair of collars 32 between which is mounted a holder 34 having therein slide-ways for another pair of slides 36 arranged to serve as rests for the bottom of the insole at or near the ball of the last and likewise having forwardly projecting end portions for overlapping the edge of the insole. The slides 36, like the slides 24, are provided with rack teeth arranged respectively to engage the opposite sides of another pinion 38 formed on the shaft 28, so that the slides 36 are adjusted toward or from each other simultaneously with the slides 24. To accommodate the shoe rest to different lengths of shoes, the slides 36 are adjustable upwardly or downwardly by lengthwise movement of the shaft 28 in its bearings, the holder 34 being movable with the shaft since it is held between the fixed collars 32. In the knurled head 30 there are provided, as shown in Fig. 4, different series of depressions 40 at different levels to receive the end of a spring-controlled plug 42 for holding the shaft 28 in different adjusted positions, in respect both to its vertical movements and to its turning movements. It will be seen that when the shaft 28 is properly adjusted the shoe is positioned with substantial accuracy by the members 24 and 36 in respect to lengthwise, lateral and angular movements.

For pulling the upper over the last there are provided grippers for gripping the upper respectively at the end of the toe and at the opposite sides of the forepart. The toe gripper comprises a gripper bar 44 which is mounted for horizontal sliding movements in a block 46 hereinafter more particularly referred to in connection with the wiping means. Fast on the bar 44 is an inner gripper jaw 48, and pivotally mounted at 50 on the bar is an outer gripper jaw 52. The jaw 52, in the construction shown, is connected by a link 54 to a rod 56 mounted for lengthwise movements within the bar 44 for effecting closing and opening movements of the jaw 52, as more particularly hereinafter described, although the invention is not dependent upon the use of the particular means illustrated for controlling the closing and opening of the grippers. The bar 44 is extended rearwardly through a bracket 58 on the frame and is pro-

vided at its rear end with rack teeth engaged by a pinion 60 which is fast on a shaft 62. Also fast on the shaft 62 is the outer member 64 of a cone clutch, the inner member 66 of which is rotatably mounted on the shaft 62 and has fast thereon a pinion 68 engaged by a gear sector 70 formed on a lever 72. On the lower end of the lever 72 is a roll 74 engaged by a cam formed in one side of a cam wheel 76 which is fast on a cam shaft 78. The clutch member 66 is held yieldingly in engagement with the member 64 by a spring 80, the tension of which is adjustable by means of a hand wheel 82 threaded on the shaft 62. It will thus be seen that lengthwise upper-pulling movement is imparted to the gripper bar 44 through the clutch members 64 and 66 which are held yieldingly in frictional engagement with each other by the spring 80. The interengaging faces of the clutch members are preferably serrated, as illustrated in Fig. 9, to increase the resistance to relative slipping movement of the members. The tension of the spring 80, however, is preferably so adjusted that the member 66 will slip relatively to the member 64 when the upper has been subjected by the gripper to substantially the required tension. It will thus be seen that pulling movement is imparted positively to the gripper until a predetermined degree of tension has been attained, whereupon the clutch begins to slip and by reason of the serrated formation of its interengaging faces imparts to the gripper a series of supplementary pulling impulses until the operating member 72 arrives at the limit of its movement. Thereafter the gripper is held by the clutch with the upper under tension until the release of the upper is effected, as herein-after described. When the parts are returned to starting position, a lug 84 on the gripper bar 44 is carried into engagement with an adjustable stop 86 on the member 46 to determine the proper starting position of the gripper, and when the movement of the gripper bar 44 is thus stopped, the clutch member 66 slips relatively to the member 64 until it assumes its initial relation to the latter.

For closing the gripper on the upper there is provided in the bar 44 (Fig. 4) a spring 88 arranged to act on the rod 56 to move the rod toward the left and thus to operate the link 54 with a toggle action to swing the jaw 52 toward the jaw 48. In order to maintain the jaw 52 initially in open position, the rod 56 carries a pin 90 which projects through slots 92 in the opposite sides of the bar 44 in position to engage the block 46. It will be understood that when the gripper is returned to starting position, as hereinbefore described, the pin 90 is carried into engagement with the block 46 before the lug 84 engages the stop 86, whereupon movement of the rod 56 is stopped and opening movement of the

gripper is effected in response to the continued movement of the bar 44.

For pulling the upper at the opposite sides of the forepart, the machine herein shown is provided with a single gripper at each side which is similar to the toe gripper in its construction and in the manner in which it is operated and controlled. Each of the opposite side grippers comprises a gripper bar 94 guided in an opening 95 (Fig. 2) in the block 46 and having thereon a fixed jaw 96 and a pivoted jaw 98, the latter being controlled in its closing and opening movements by mechanism not shown in detail, since it is substantially like the mechanism above described for controlling the jaw 52 of the toe gripper. This mechanism includes a pin 100 projecting upwardly through a slot in the bar 94 and arranged to engage the block 46 to hold the jaw 98 initially in open position. Each of the openings 95 in the block 46 is so formed as to prevent movements of the corresponding side gripper bar 94 laterally of the shoe, but is sufficiently wide vertically to permit the bar to swing lengthwise of the shoe, as required for tip straightening. To permit such swinging movement, each bar 94 is pivoted at 102 to a slide 104 mounted in a guideway in the bracket 58.

Each of the opposite side grippers is operated through a separate friction clutch similar to the clutch hereinbefore described for operating the toe gripper. Each clutch comprises a clutch member 106 (Fig. 3) mounted for turning movement on a shaft 108 which extends transversely of the bracket 58, and fast on each of the clutch members 106 is a pinion 110 in engagement with rack teeth formed on the lower face of the corresponding slide 104 (Fig. 2). In engagement with one of the clutch members 106 is a co-operating clutch member 112 which is fast on the shaft 108; and in engagement with the other clutch member 106 is a co-operating clutch member 114 which is mounted for sliding movement lengthwise of the shaft 108 but is forced to turn with the shaft by means of a pin 116 which projects from the shaft into a slot 118 in the clutch member. A spring 120 is mounted on the shaft 108 between the clutch member 114 and a hand wheel 122 that is threaded on the shaft and serves to adjust the tension of the spring. It will be seen that the spring 120 thus tends to move the clutch member 114 and the shaft 108 in opposite directions, and thereby to hold both the clutch members 112 and 114 in engagement with their co-operating clutch members 106 with a force determined by adjustment of the wheel 122. The members of each clutch are preferably provided with serrated faces similar to the interengaging faces of the clutch which operates the toe gripper, so that each side gripper will be operated positively until the upper has been subjected to a predeter-

mined degree of tension and will then be subjected to supplementary pulling impulses by reason of relative slipping movement of the members of its operating clutch.

5 The means for operating the two opposite side clutches comprises a gear sector 124 in engagement with gear teeth 126 formed on the clutch member 112, the gear sector 124 being formed on a lever 128 provided on its 10 lower end with a roll 130 which is operated by a cam formed in one side of a cam wheel 132 fast on the shaft 78. It will be evident that in the upper-pulling operation either of the opposite side clutches may slip independently of the other when the upper has been subjected to a predetermined tension, and that since both clutches are controlled by the same spring 120, the upper will finally be subjected to substantially the same degree of 15 tension at the opposite sides of the forepart. Each of the opposite side gripper bars 94 has on its lower face a lug 134 (Fig. 2) arranged to engage an adjustable stop 136 on the block 46 to determine the initial position of the gripper and to cause the parts of the controlling clutch to assume their initial relation to each other before the machine comes to a stop at the end of the cycle.

20 As more particularly hereinafter described, the machine is so controlled as to come automatically to a stop at the end of the upper-pulling movement of the grippers to permit the operator to inspect the work prior to the wiping and fastening operations, and 25 the machine is provided with means which may be utilized while the machine is thus at rest for effecting relative movements of the opposite side grippers lengthwise of the last to straighten the tip. This means comprises 30 a hand lever 138 which is fast on a rock shaft 140 having thereon oppositely disposed eccentrics 142 connected by links 144 to the respective side gripper bars 94. Movement of the 35 lever 138 in one direction thus serves to move the opposite side grippers respectively in opposite directions lengthwise of the shoe to 40 adjust the upper. It will be understood that the friction of the parts and the character of 45 the eccentric connections are such as to retain the side grippers in adjusted position.

50 After the upper-pulling operation the upper is subjected at the end of the toe and at the sides of the forepart to an upwiping operation, after which its margin is wiped inwardly over the bottom of the last in these 55 different locations into position to be fastened. The wiping means is mounted on the block 46 which, for this purpose, is provided with a front arm 146 extending forwardly 60 over the toe gripper and with opposite side arms 148 extending forwardly adjacent to the side grippers. On the front arm 146 there is mounted for sliding movement toward and 65 from the toe of the shoe a wiper 150 comprising a plate having its inner end faced with

comparatively soft material, such as leather, for engagement with the upper to upwipe the upper toward the edge of the last bottom. Adjacent to the wiper 150 there is mounted a wiper 152 for wiping the upper inwardly 70 over the bottom of the last, this wiper having its inner end turned rearwardly to guide it over the edge of the shoe bottom. Spring plungers 154 press the wiper 152 against the wiper 150 while permitting the wiper 152 to 75 tip in response to resistance of the shoe materials as it is moved inwardly over the shoe bottom. In each of the side arms 148 there are similarly mounted an upwiping wiper 156 and an overwiping wiper 158, these wipers, 80 except as to width and end contour, being substantially like the wipers 150, 152 at the end of the toe. Each of the wipers 158 is controlled by spring plungers 160 in the same manner as the toe end wiper 152. 85

The wipers 150 and 156 are moved inwardly against the upper, by mechanism herein-after described, while the upper is held under tension by the grippers, and thereafter the upwiping operation is effected by rearward 90 movement of the block 46 which carries the wipers. For this purpose the block 46 is secured to rods 162 which are mounted for horizontal sliding movements in bearings formed in the frame of the machine. For 95 imparting to the block 46 its rearward upwiping movement it is connected by a link 164 to a bell crank lever 166 provided with a roll 168 engaged by a cam formed in one side of the cam wheel 76. 100

For moving the wiper 150 downwardly into engagement with the toe end of the shoe, there is mounted on an upward extension of the arm 146 a slide 170 having thereon an arm 172 which is forked for engagement with pins 105 174 projecting from opposite sides of a block 176 slidingly mounted on a rod 178 which projects upwardly from the wiper 150. The block 176 is mounted between a nut 180 on the rod 178 and a spring 182 through which movement is imparted yieldingly to the wiper 150. The slide 170 is operated by a lever 184 which is pivoted at 186 on a bracket 188 extending upwardly from one of the side arms 148, one end of the lever being forked to engage a pin 110 190 projecting from the slide 170. The lever 184 is swung downwardly against the resistance of a spring 192, to move the wiper 150 into engagement with the shoe, by means of a cam 194 mounted on the upper end of a 115 shaft 196 which turns in bearings formed in the bracket 188, the cam 194 being arranged to engage a roll 198 on the lever. The shaft 196 at its lower end is connected by a universal joint to a telescopic shaft 200 which is connected in turn by a universal joint to a shaft 202 mounted in a bearing on the frame of the machine. Fast on the shaft 202 is a pinion 204 operated by a rack bar 206 which is provided at its rear end with a roll 208 engaged 120 125 130

by a cam formed in one side of a cam wheel 210 which is fast on the shaft 78. It will be understood that this cam serves, through the connections described, to move the wiper 150 into engagement with the shoe, and that by means of the telescopic shaft 200 and the universal joints at the opposite ends thereof, operative connection between the cam and the lever 184 is maintained in all positions of the 10 movable block 46.

A portion of the mechanism above described for moving the end wiper 150 downwardly is also utilized to move the side wipers 156 into engagement with the shoe. For controlling 15 one of the side wipers there is provided a transverse rack bar 212 operatively engaged at one end by a pinion 214 on the shaft 196 and engaging at its other end a pinion 216 on a rock shaft 218. The shaft 218 carries a 20 lever arm 220 which is forked to engage pins 222 on the opposite sides of a block 224 slid- 25 ingly mounted on a rod 226 which is fast on the wiper 156, a spring 228 being interposed between the block 224 and the wiper for im- 30 parting inward movement yieldingly to the wiper, and the rod 226 having a nut 229 there- 35 on to be engaged by the block 224 for moving the wiper outwardly. The opposite side wiper 156 is moved inwardly toward the shoe by 40 similar mechanism, comprising a lever arm 220 and a spring 228, this lever arm being fast on the shaft 196.

The wipers 152 and 158 for wiping the margin of the upper inwardly over the bottom 35 of the fast at the end and the sides of the forepart are operated by the same means which moves the upwiping wipers inwardly against the shoe. The wiper 152 has a laterally projecting outer end portion through 45 which loosely extends a threaded rod 230 pivotally mounted on the wiper-operating member 172, this rod having nuts 232 thereon which are spaced from each other at opposite sides of the projection on the wiper to pro- 50 vide a lost motion connection between the member 172 and the wiper 152, so that the wiper 150 may be forced yieldingly into engagement with the shoe and held in such engagement during the upwiping operation be- 55 fore the wiper 152 is forced inwardly over the bottom of the shoe. Between the side wipers 158 and the operating arms 220 there are similar lost motion connections, comprising threaded rods 234 pivoted on the arms 220 and provided with spaced nuts substantially as in the mechanism provided for op- 60 erating the end wiper 152.

Before the wipers 152 and 158 are forced inwardly over the bottom of the shoe, the toe 65 and side grippers are made to release their hold on the upper. It will be understood that, at the beginning of the operative movement of the gripper bars 44 and 94, the pins 90 and 100, which are mounted on the rods which 70 control the pivoted gripper jaws as hereinbe-

fore described, are held in engagement with the block 46 until the gripper jaws have been closed on the upper, whereupon these pins are moved out of engagement with the block as the grippers are operated to pull the upper. 75 The movement which the block 46 thereafter receives in operating the wipers 150 and 156 to upwipe the upper carries it toward the pins 90 and 100 on the grippers, but not so far as would cause it, under all conditions, to 80 effect the opening of the gripper jaws by engagement with the pins. For opening the gripper jaws there are, accordingly, provided arms 236 which are pivotally mounted on the frame of the machine and are provided with inner end portions which lie in recesses formed in the rear face of the block 46 between the block and the pins 100 on the side grippers, as shown by dotted lines in Fig. 3. It will be seen that the ends of these arms 85 are extended far enough to project also by the opposite ends of the pin 90 on the toe gripper. Mounted in the block 46 are screws 238, the heads of which are arranged to engage the lever arms 236 near the fulcrum points of these arms and thus to impart to the arms, in the operative movement of the block 46, such swinging movement as to carry their inner ends away from the rear face of the block and thus cause them to operate 90 on the pins 90 and 100 to open the toe and side grippers in the upwiping movement of the wipers 150 and 156. Preferably the screws 238 will be so adjusted as to cause the grippers to open and release the upper when 95 the wipers have arrived substantially or nearly at the end of their upwiping movement. The arms 236 are held in engagement with the screws 238 by springs 240. 100 For supporting the shoe against the pressure of the overwiping and fastening means there is provided a clamping device comprising an arm 242 mounted on the front end of one of the rods 162 hereinbefore referred to as movable lengthwise with the block 46. 110 The arm 242 carries a pad 244 of yieldable material such as rubber faced with leather for engaging the shoe at the top of the forepart, and the arm is mounted to swing about the rod 162 from an idle position in which the 115 pad 244 is at one side of the shoe, as shown in Figs. 1 and 2, to a position in which the pad is in front of the forepart of the shoe. The hub of the arm 242 carries a projection 246 which is arranged to engage a lug 248 formed on a collar which is fast on the rod 162 to determine the idle position of the arm, and a spring 250 is arranged to act on the projection 246 to hold the arm in idle position. 120 The arm 242 is swung by the operator into position to present the pad 244 in front of the shoe before the machine is started to effect the upwiping operation, and as the block 46 and the rods 162 are moved toward the rear to cause the wipers 150 and 130

156 to upwipe the upper, the pad 244 is forced firmly into engagement with the shoe. The pad 244 is mounted on a bar 252 which is slideable in the arm 242, and a spring 254 acts 5 on this bar to hold the pad in retracted position. After swinging the pad into position in front of the shoe, the operator may push on the outer end of the bar 252 to move the pad toward the shoe before starting the machine, the pad being held in the position to which the operator moves it by means of a pawl 256 in engagement with rack teeth formed on the bar 252. The comparatively short movement which the supporting rod 162 10 receives in the upwiping operation then serves to force the pad firmly into engagement with the shoe. In the return of the parts to starting position the arm 242 is swung to one side by the spring 250 after 15 the pressure of the pad 244 upon the shoe has been relaxed, and by means of a handle 258 the pawl 256 is made to release the rod 252, thereby permitting the pad to be retracted by the spring 254.

20 25 For fastening the upper in pulled over position after the overwiping operation, the machine herein shown is provided with means permanently positioned in a location opposite to the bottom of the shoe for driving a single tack at the end of the toe and three tacks at each side of the forepart through portions of the upper that are acted upon by the wipers 152 and 158, these wipers being provided with slots to permit the driving 25 of the tacks, as shown by dotted lines in Fig. 1. One of the side tacking mechanisms is shown in detail in Fig. 5, the tacking mechanisms at the opposite sides being identical except for differences in shape required by 30 the contour of the shoe. Mounted for lengthwise sliding movement in the block 46 and in the fixed bracket 58 is a driver bar 260 which carries at its front end three tack 35 holders or nozzles 262 and a corresponding number of tack drivers 264 within the holders. The tack holders 262 are slidably mounted in sockets formed in a driver block or head 266 which is carried by an enlarged end portion of the driver bar 260, the block 266 having 40 threaded therein sleeve members 268 which form bearings for the tack holders and are engaged by enlarged heads 270 on the inner ends of the holders to limit outward movement of the latter. The drivers 264 are 45 provided with heads 272, and between these heads and the heads 270 on the tack holders are mounted springs 274 which tend to retract the drivers and at the same time force the tack holders outwardly in the block 266.

50 55 60 65 60 In the tack-driving operation the driver bar 260 carries the ends of the tack holders 262 into engagement with the corresponding wiper plate 158, and by continued movement then forces the block 266 and the drivers 264 toward the shoe to drive the tacks.

In order to facilitate the delivery of tacks to the tack holders 262, the latter are mounted for tipping or turning movement from their substantially horizontal tack-driving positions, as illustrated in Fig. 5, to substantially vertical tack-receiving positions, as shown in full lines in Fig. 4. For this purpose the block 266 is provided with an arc-shaped flange 276 which is movable in a corresponding guideway formed in the head portion of the bar 260, and on the block are provided a series of gear teeth 278 in engagement with the teeth of a rack bar 280 which is slidably movable in the block 46 and extends also through a guideway in the head of the bar 260. The normal position of the rack bar 280 is determined by a stop screw 282 and a spring 284, the latter acting on the rack bar to hold the screw 282 in engagement with the block 46. When the driver bar 260 is moved toward the right from the position in which it is shown in Fig. 5, the block 266 with its tack holders and drivers is retracted and is, at the same time, turned by the action of the rack bar 280 on the teeth 278 into the position 70 illustrated in Fig. 4, in which the outlet ends of the tack holders 262 are directed vertically upward into position to receive tacks dropped head downward from flexible tubes 286 communicating with openings formed in the arm 146. When the driver bar 260 is moved toward the left from the position in which it is shown in Fig. 4, the tack holders are swung 75 downwardly to horizontal position, this swinging movement of the tack holders being 80 limited by engagement of a lug 288 on the block 266 with a lug 290 on the end of the rack bar 280. In the tack-driving operation the driver bar 260 is moved farther toward the left from the position of Fig. 5 and 85 in this operation the rack bar 280 is carried along with the driver bar against the resistance of its spring 284.

The mechanism for driving the tack at the end of the toe differs somewhat in detail 90 from the mechanism for driving the side tacks, as illustrated in Fig. 6. Slidably mounted in the block 46 is a toe driver bar 292 immediately under the toe gripper bar 44, the bar 292 carrying at its front end a 95 driver block 294 in which is slidably mounted a tack holder 296 and a driver 298 in substantially the same manner as the corresponding parts for driving the side tacks, as 100 illustrated in Fig. 5. The driver block 294 is pivoted at 300 on the end of the bar 292, and in the tack-driving operation occupies a 105 position partly within a recess 302 in the driver bar with the tack holder substantially horizontal, as shown in Fig. 6. The driver block 294 is connected by a link 304 to a rod 306 which is slideable in the block 46 and is provided with a stop screw 308 and a spring 310 for determining the normal position of 110 the rod, similarly to the construction shown 115

in Fig. 5. In Fig. 6 the parts are shown in the positions which they assume as the tack holder is being moved horizontally toward the shoe, the rod 306 being carried along with the driver bar 292. It will be understood that the end of the tack holder is carried into engagement with the toe wiper plate 152, and that by continued movement of the driver bar the block 294 and the driver 298 are moved relatively to the tack holder to drive the tack. In the return of the parts the stop screw 308 is carried into engagement with the block 46, whereupon further movement of the bar 292 toward the right acts to swing the block 294 with its tack holder and driver to a substantially vertical position to receive the tack, as shown in full lines in Fig. 4. To provide space for the upward swinging movement of the toe tack holder 296, the toe gripper bar 44 and the rod 56 therein are provided with slots extending lengthwise thereof, as indicated by dotted lines at 311 in Fig. 4.

The means for delivering the tacks to the several tack holders through the flexible tubes 286 may comprise any suitable tack-separating and delivering mechanism, and accordingly such mechanism is not shown herein in detail. In Fig. 8 is illustrated one form of device which may be utilized to invert the tacks so as to deliver them head downward. This device comprises an oscillatory member 312 provided with a plurality of tack-receiving recesses 314 corresponding in number to the number of tacks to be driven at each operation, the tacks being delivered point downward to these recesses from suitable separating mechanism through tubes 316. The member 312 is turned at a predetermined time in the cycle to drop the tacks head downward into the flexible tubes 286.

The mechanism for operating the driver bars 260 and 292 comprises a bell crank lever 318, the upper end of which is forked, as shown in Fig. 3, for engagement with the opposite ends of a pin 320 which extends through both the opposite side driver bars 260. Carried by the pin 320 is also a bracket 322 which is fast on the rear end of the toe driver bar 292. It will thus be seen that the three driver bars are operated simultaneously by the lever 318. On its lower end the lever 318 is provided with a roll 324 engaged by a cam formed in one side of the cam wheel 132. For operating the cam shaft 78 and for controlling the operation of the machine any suitable means may be utilized, a convenient arrangement of mechanism for this purpose being shown in detail in Fig. 7. Mounted for turning movement about a sleeve on the shaft 78 is a belt pulley 326 which is formed to serve as one member of a clutch, and a co-operating clutch member 328 is splined on a sleeve 330 on the shaft, a spring 332 being provided for holding this member out of engagement with the pulley.

Fast on the sleeve 330 is a gear wheel 334 which acts through connecting gear wheels 336 and 338 to transmit movement to a gear wheel 340 fast on the cam shaft 78. It will thus be seen that when the clutch member 328 is being driven by the pulley 326, the shaft 78 is turned at a considerably lower rate of speed than the pulley by reason of the relative sizes of the different gear wheels.

The clutch member 328 is forced into engagement with the pulley 326 by means of a vertically movable wedge member 342 connected to a lever 344 which is acted upon by a spring 346 to force the wedge member 342 downwardly and thus to set the clutch, and is provided with a brake shoe 348 for engaging the member 328 to stop the machine when the clutch is released. As the parts are positioned in Fig. 7, the lever 344 is held in its uppermost position with the brake applied and the clutch released. For holding the lever 344 in this position there is provided a lever 350 having thereon a roll engaged by a stop cam 352 on the cam shaft 78, this lever having projecting therefrom an arm 354 which acts through a pair of toggle members or links 356 on an arm 358 projecting from the lever 344. It will be seen that, as the parts are positioned in Fig. 7, the toggle members 356 are in alignment with each other so that a rigid connection is provided between the arm 354 and the arm 358. In order to start the machine, there is provided means for breaking the toggle 356, thus releasing the lever 344 to the action of its spring 346, one of the toggle members 356 having therein a slot 360 which forms part of the connection between it and the arm 354 and affords sufficient play to permit the breaking of the toggle. The breaking of the toggle is effected by means of a treadle 362 which acts to raise a treadle rod 364 against the resistance of a spring 366, this rod having upon its upper end a member 368 which engages the lower end of a vertically slidable rod 370 and acts to raise this rod against the resistance of a spring 372 when the treadle is depressed, the rod 370 being connected to the knee joint of the toggle by means of a link 374.

Immediately upon the starting of the machine the lever 350 is released by the cam 352, so that the arm 354 is swung to the left far enough to permit the straightening of the toggle 356 by the action of the spring 372 when the treadle is released by the operator. A rigid connection between the lever 350 and the lever 344 is thus re-established, so that when another stop cam 376 arrives in position to engage the roll on the lever 350, the clutch is released and the brake is applied to stop the machine. Mechanism is also provided for insuring that the machine will stop at this point, even though the operator

should continue to hold the treadle depressed. For this purpose the member 368 is pivotally mounted on the rod 364 to permit it to swing out from under the rod 370 and thus to release the latter. Such swinging movement of the member 368 is effected immediately after the starting of the machine by the action of the stop cam 352 (or later the stop cam 376) on a lever 378, this lever being connected by a link 380, crank arms 382 and 384, and a link 386 to the member 368. When the lever 378 is released by the cam, a spring 388 swings the member 368 back again into position for it to project under the end of the rod 370 when the operator releases the treadle.

In the operation of the machine, briefly summarized, the operator adjusts the shoe rest for the size and style of shoe upon which the machine is to operate, and presents the shoe in the position illustrated in Fig. 2 with the margin of the upper projecting within the open gripper jaws. While supporting the shoe with one hand, the operator depresses the treadle 362 to start the machine, whereupon the gripper bars 44 and 94 begin their rearward movement. As the gripper bars start their rearward movement, the spring 88 in the toe gripper bar and the corresponding springs in the side gripper bars act to close the gripper jaws upon the upper. In the continued movement of the gripper bars the upper is pulled positively through the action of the clutches hereinbefore described, and when the upper has been subjected to the degree of tension for which the different clutches are adjusted, the co-operating clutch members begin to slip relatively to each other and the upper is thus subjected to supplementary pulling impulses by reason of the serrated formation of the clutch faces. At the end of the upper-pulling operation the machine is brought automatically to a stop by the action of the stop cam 376 on the lever 350. The operator is then enabled to inspect the shoe and to make any tip straightening adjustment that may be needed by manipulation of the lever 138.

Before starting the machine for the second time, the operator swings the shoe-supporting pad 244 into position in front of the shoe and moves the pad forwardly toward, and it may be substantially into engagement with, the shoe, by pushing on the bar 252. He then again depresses the treadle to start the machine, whereupon the wipers 150 and 156 are moved inwardly into engagement with the shoe at the toe end and at the sides of the forepart at a substantial distance from the edge of the shoe bottom, as illustrated in Fig. 10. The wiper-supporting block 46 is then moved toward the rear, thus imparting to the above-mentioned wipers upwiping movement toward the edge of the shoe bottom. Near the end of this upwiping movement of the wipers

the grippers are made to open and release the upper by the action of the arms 236 on the pins 90 and 100. By further movement of the wiper-operating means the wipers 152 and 158 are then forced inwardly to wipe the margin of the upper over the insole, as illustrated in Fig. 11, the holding pressure of the wipers 150 and 156 on the upper being simultaneously increased to insure against loss of tension.

After the upper has thus been wiped inwardly over the insole, operative movement is imparted to the tacking mechanism to fasten the upper. In this operation the tack holders 262 and 296 are moved horizontally toward the shoe and into engagement with the wiper plates 158 and 152, and by continued movement of the driver bars 260 and 292 the tacks are positively driven into the shoe to the required distance. Thereafter the parts of the machine begin their return movements to starting position. In the return movements of the tacking mechanisms the tack holders are tipped upwardly to vertical positions in the manner hereinbefore described to receive tacks which are then delivered into their outlet ends, and by reverse movement of the driver bars the holders are then tipped downwardly to horizontal positions ready to operate on the next shoe. In the return of the wipers to starting position, they are first moved outwardly away from the shoe and are then carried forwardly by movement of the block 46. It will be understood that at the time when the tack holders are tipped upwardly into tack-receiving position the block 46 is held stationary with its tack-delivering openings in alignment with the respective tack holders.

It should be understood that for the fastening of the upper the invention is not dependent upon the use of fastenings of the particular form herein shown, and the term "tack" and similar terms are accordingly used in the claims for convenience of designation and not by way of limitation.

Having fully described my invention, what I claim as new and desire to secure by Letters Patent of the United States is:

1. A machine of the class described having, in combination, means for pulling an upper over a last, a plurality of wipers arranged to engage the upper respectively in different spaced locations about the forepart of the last with their wiping faces extending substantially heightwise of the last to upwipe the upper, and means for imparting bodily to said wipers operative wiping movement heightwise of the last while the upper is held under tension by the pulling means.

2. A machine of the class described having, in combination, grippers for gripping and pulling an upper respectively at the toe end and at the opposite sides of the forepart of a last, a plurality of wipers arranged to engage

the upper respectively in different spaced locations at the end and the sides of the forepart for upwiping the upper, and means for effecting relative movement of the last and said wipers to upwipe the upper while the upper is held under tension by the grippers.

3. A machine of the class described having, in combination, grippers for gripping and pulling an upper respectively at the toe end and at the opposite sides of the forepart of a last, power-operated means for effecting relative movement of said grippers and the last to pull the upper, means for bringing the machine automatically to a stop after the upper-pulling operation, and means automatically operative upon a subsequent starting of the machine to wipe the upper heightwise of the last in different spaced locations at the end of the toe and at the sides of the forepart.

20 4. A machine of the class described having, in combination, grippers for gripping and pulling an upper respectively at the toe end and at the opposite sides of the forepart of a last, wipers arranged to engage the upper respectively in different spaced locations at the end of the toe and the sides of the forepart, power means for operating said grippers to pull the upper, means for bringing the machine automatically to a stop after the upper-pulling operation, and means automatically operative upon a subsequent starting of the machine to move said wipers into engagement with the upper and to operate them to upwipe the upper.

35 5. A machine of the class described having, in combination, grippers for gripping and pulling an upper respectively at the toe end and at the opposite sides of the forepart of a last, a plurality of wipers arranged to engage the upper respectively in different spaced locations at the end and the sides of the forepart for upwiping the upper, means for wiping the margin of the upper inwardly over the bottom of the last, and means for effecting relative movement of the last and said wipers to upwipe the upper after the upper-pulling operation and prior to the overwiping operation.

60 6. A machine of the class described having, in combination, means for pulling an upper over a last, a plurality of wipers arranged to engage the tensioned upper respectively in different spaced locations about the forepart of the last, with their wiping faces extending substantially heightwise of the last, to upwipe the upper, means for wiping the margin of the upper inwardly over the bottom of the last, and means for imparting bodily to said wipers operative wiping movement heightwise of the last prior to the overwiping operation.

65 7. A machine of the class described having, in combination, means for pulling an upper over a last, a plurality of wiper-supporting arms arranged to extend heightwise

of the last in different locations about the forepart and having thereon wipers for engaging the upper respectively in different spaced locations on the lateral periphery of the last, and means for moving said arms heightwise of the last to cause the wipers to wipe the tensioned upper toward the edge of the last bottom.

8. A machine of the class described having, in combination, grippers for gripping and pulling an upper respectively at the toe end and at the opposite sides of the forepart of a last, a wiper carrier having thereon a plurality of arms arranged to extend heightwise of the last adjacent to the toe and side grippers and carrying wipers for engaging the upper respectively at the end of the toe and the sides of the forepart, and means for moving said wiper carrier heightwise of the last after the upper-pulling operation to cause the wipers to wipe the upper toward the edge of the last bottom.

9. A machine of the class described having, in combination, means for pulling an upper over a last, a plurality of wiper-supporting arms arranged to extend heightwise of the last and having wipers movably mounted thereon for engaging the upper respectively in different spaced locations on the lateral periphery of the last, and means for moving said wipers relatively to the arms into engagement with the upper and for thereafter moving said arms heightwise of the last to cause the wipers to upwipe the upper.

10. A machine of the class described having, in combination, means for pulling an upper over a last, a plurality of wiper-supporting arms arranged to extend heightwise of the last and fixed against movement toward or from the last, wipers movably mounted on said arms for engaging the upper respectively in different spaced locations on the lateral periphery of the last, and means for moving said wipers into engagement with the upper and for effecting relative movement of said arms and the last heightwise of the last to cause the wipers to upwipe the upper.

11. A machine of the class described having, in combination, means for pulling an upper over a last, a wiper carrier having thereon arms arranged to extend heightwise of the last at the toe end and the sides of the forepart and fixed against movement toward or from the last, wipers movably mounted on said arms for engaging the upper respectively in different spaced locations on the lateral periphery of the last, means for moving said wipers inwardly into engagement with the upper, and means for operating said wiper carrier to cause the wipers to upwipe the upper.

12. A machine of the class described having, in combination, means for pulling an

upper over a last, a wiper carrier having thereon wipers for engaging the upper respectively in different spaced locations about the last with their wiping faces extending substantially heightwise of the last, means for moving said wiper carrier heightwise of the last to cause the wipers to upwipe the upper, and means on said wiper carrier for moving the wipers relatively to said carrier into engagement with the upper prior to the upwiping operation.

13. A machine of the class described having, in combination, means for pulling an upper over a last, a plurality of wiper-supporting arms arranged to extend heightwise of the last and having thereon wipers for engaging the upper respectively in different spaced locations about the last, means for moving said arms heightwise of the last to cause the wipers to upwipe the upper, devices on the different arms for moving the respective wipers inwardly into engagement with the upper, and means for operating said devices in unison.

14. A machine of the class described having, in combination, means for pulling an upper over a last, a plurality of wiper-supporting members having thereon wipers for engaging the upper respectively in different spaced locations about the last, means for effecting relative movement of said members and the last to cause the wipers to upwipe the upper, wipers also mounted on said wiper-supporting members for wiping the margin of the upper inwardly over the bottom of the last, and means for operating said last-named wipers to wipe the upper inwardly after the upwiping operation.

15. A machine of the class described having, in combination, means for pulling an upper over a last, a plurality of wiper units arranged to operate upon the upper in different spaced locations about the last and each comprising an upwiping wiper and an overwiping wiper, means for effecting relative movement of said wiper units and the last to upwipe the upper, and means for thereafter operating the overwiping wipers to wipe the upper inwardly over the bottom of the last.

16. A machine of the class described having, in combination, means for pulling an upper over a last, a plurality of wiper-supporting arms arranged to extend heightwise of the last and each having movably mounted thereon an upwiping wiper and an overwiping wiper, and means on each of said arms for moving the upwiping wiper into engagement with the upper prior to the upwiping operation and for operating the overwiping wiper to wipe the upper inwardly over the bottom of the last after the upwiping operation.

17. A machine of the class described having, in combination, means for pulling an upper over a last, a plurality of wiper-supporting arms arranged in different locations about

the last and each having thereon an upwiping wiper and an overwiping wiper, a member on each of said arms for moving both wipers inwardly toward the shoe, a yielding connection between said member and the upwiping wiper, a lost motion connection between said member and the overwiping wiper, and means for operating the different members in unison.

18. A machine of the class described having, in combination, grippers for gripping and pulling an upper respectively at the end of the toe and at the opposite sides of the forepart of a last, wiper units associated respectively with the different grippers and each comprising an upwiping wiper and an overwiping wiper, and a device common to the different wipers of each unit for moving the upwiping wiper yieldingly into engagement with the upper and for thereafter imparting operative movement to the overwiping wiper.

19. In a machine of the class described, the combination with shoe-positioning means, of a wiper support, an upwiping wiper and an overwiping wiper mounted on said support for movements toward and from the shoe, a member on said support for moving both wipers inwardly toward the shoe, a yielding connection between said member and the upwiping wiper, and a lost motion connection between said member and the overwiping wiper.

20. In a machine of the class described, the combination with shoe-positioning means, of a wiper support, an upwiping wiper and an overwiping wiper mounted on said support for movements toward and from the shoe, means for moving said support heightwise of the shoe to upwipe the upper, and operating means on said support for both wipers including a yielding connection for moving the upwiping wiper inwardly into engagement with the shoe and a lost motion connection for thereafter operating the overwiping wiper.

21. In a machine of the class described, a gripper for pulling an upper over a last, and means for operating said gripper comprising an automatically controlled friction clutch having members arranged for relative slipping movement in response to resistance of the upper when the upper has been subjected to a predetermined tension.

22. In a machine of the class described, a gripper for pulling an upper over a last, and means for operating said gripper comprising an automatically controlled friction clutch having members arranged for relative slipping movement in response to resistance of the upper when the upper has been subjected to a predetermined tension, said clutch members having serrated interengaging faces for subjecting the upper to repeated pulling impulses in the relative slipping movement of said members.

23. In a machine of the class described, a gripper for pulling an upper over a last, and means for operating said gripper comprising a friction clutch having members arranged for relative slipping movement in response to resistance of the upper when the upper has been subjected to a predetermined tension, and spring means for holding said clutch members continuously in engagement with each other.

24. In a machine of the class described, a gripper for pulling an upper over a last, and means for operating said gripper comprising a friction clutch having members arranged for relative slipping movement in response to resistance of the upper when the upper has been subjected to a predetermined tension, a spring for holding said clutch members continuously in engagement with each other, and means for varying the force of said spring.

25. In a machine of the class described, a gripper for pulling an upper over a last, and means for operating said gripper comprising a friction clutch having members arranged for relative slipping movement in response to resistance of the upper when the upper has been subjected to a predetermined tension, means for holding said clutch members continuously in engagement with each other, a cam shaft, and connections between said cam shaft and clutch for operating the clutch by said cam shaft.

26. In a machine of the class described, a gripper for pulling an upper over a last, said gripper being mounted for rectilinear upper-pulling movement, and a friction clutch geared directly to said gripper for operating it, said clutch comprising clutch members arranged for relative slipping movement in response to resistance of the upper when the upper has been subjected to a predetermined tension.

27. In a machine of the class described, a gripper for pulling an upper over a last, and means for operating said gripper comprising an automatically controlled friction clutch connected positively to the gripper, said clutch comprising clutch members arranged for relative slipping movement in response to resistance of the upper when the upper has been subjected to a predetermined tension.

28. In a machine of the class described, a gripper for pulling an upper over a last, and means for operating said gripper comprising an automatically controlled friction clutch connected positively to the gripper, said clutch comprising clutch members arranged for relative slipping movement in response to resistance of the upper when the upper has been subjected to a predetermined tension and having serrated interengaging faces for subjecting the upper to repeated pulling impulses in the relative slipping movement of said members.

29. In a machine of the class described,

grippers for pulling an upper respectively at the opposite sides of a last, and automatically controlled friction clutches connected respectively to the different grippers for operating them, each clutch comprising members arranged for relative slipping movement in response to resistance of the upper when the upper has been subjected to a predetermined tension.

30. In a machine of the class described, grippers for pulling an upper respectively at the opposite sides of a last, friction clutches connected respectively to the different grippers for operating them, each of said clutches comprising clutch members arranged for relative slipping movement in response to resistance of the upper when the upper has been subjected to a predetermined tension, spring means for holding the members of each clutch yieldingly in engagement with each other, and means for operating both clutches simultaneously.

31. In a machine of the class described, grippers for pulling an upper respectively at the opposite sides of a last, separate friction clutches connected respectively to the different grippers for operating them, each of said clutches comprising clutch members arranged for relative slipping movement in response to resistance of the upper when the upper has been subjected to a predetermined tension, and a spring common to both clutches for holding the members of each clutch yieldingly in engagement with each other to equalize substantially the forces applied to the upper at the opposite sides of the last.

32. In a machine of the class described, grippers for pulling an upper respectively at the opposite sides of a last, friction clutches connected respectively to the different grippers for operating them and each comprising clutch members arranged for relative slipping movement in response to resistance of the upper when the upper has been subjected to a predetermined tension, a cam shaft, and a connection operated by said cam shaft and common to both clutches for operating the grippers through said clutches.

33. In a machine of the class described, a plurality of grippers for gripping and pulling an upper respectively at the toe end and at the opposite sides of the forepart of a last, and a plurality of automatically controlled friction clutches connected respectively to the different grippers for operating them, each of said clutches comprising clutch members arranged for relative slipping movement in response to resistance of the upper when the upper has been subjected to a predetermined tension.

34. In a machine of the class described, a plurality of grippers for gripping and pulling an upper respectively at the toe end and at the opposite sides of the forepart of a last, a plurality of friction clutches connected

respectively to the different grippers for operating them, each of said clutches comprising clutch members arranged for relative slipping movement in response to resistance of the upper when the upper has been subjected to a predetermined tension, spring means for holding said clutch members yielding in engagement with each other, a cam shaft, and connections between said cam shaft and the the clutches for operating the grippers through the clutches.

35. In a machine of the class described, a plurality of grippers for gripping and pulling an upper respectively at the toe end and at the opposite sides of the forepart of a last, a plurality of friction clutches connected respectively to the different grippers for operating them, each of said clutches comprising clutch members arranged for relative slipping movement in response to resistance of the upper when the upper has been subjected to a predetermined tension, and automatic means for operating all of said clutches simultaneously to pull the upper.

25 36. In a machine of the class described, the combination with means for pulling an upper over a last, of upper-fastening mechanism comprising a tack holder movable from tack-driving position to tip its outlet end upwardly to receive a tack, and means for delivering a tack to said tack holder through its outlet end.

35 37. In a machine of the class described, the combination with means for pulling an upper over a last, of upper-fastening mechanism comprising a tack-holding nozzle movable from a substantially horizontal tack-driving position into a position at a substantial angle to the line of drive with its outlet end directed upwardly to receive a tack, and means for delivering a tack to said nozzle through its outlet end.

45 38. In a machine of the class described, the combination with means for pulling an upper over a last, of upper-fastening mechanism comprising a tack-holding nozzle movable through an angle of substantially ninety degrees from tack-driving position to tack-receiving position, and means for delivering a tack to said nozzle through its outlet end in said last-named position.

55 39. In a machine of the class described, the combination with means for pulling an upper over a last, of upper-fastening mechanism comprising a tack holder mounted for movement from a position to permit a tack to be driven in a substantially horizontal direction into a position at a substantial angle to the line of drive with its outlet end directed upwardly to receive a tack, and automatic means for imparting said movement to the tack holder.

60 40. In a machine of the class described, the combination with means for pulling an upper

over a last, of upper-fastening mechanism comprising a tack holder movable from tack-driving position to tip its outlet end upwardly to receive a tack, automatic means for thus tipping the tack holder, and means for delivering a tack to said tack holder through its outlet end.

41. In a machine of the class described, the combination with means for pulling an upper over a last, of upper-fastening mechanism comprising a tack-holding nozzle movable from tack-driving position into a position in which it is directed generally lengthwise of the last to receive a tack, and means for delivering a tack to the nozzle in said last-named position.

80 42. In a machine of the class described, the combination with means for pulling an upper over a last, of tacking mechanisms for driving tacks at the opposite sides of the forepart of the last to fasten the upper, said tacking mechanisms comprising tack holders each movable about an axis extending laterally of the last from tack-driving position into a position at a substantial angle to the line of drive to receive a tack, and means for delivering tacks to said tack holders when the latter are in tack-receiving position.

90 43. In a machine of the class described, the combination with means for pulling an upper over a last, of tacking mechanisms for driving tacks at the opposite sides of the forepart of the last to fasten the upper, each of said opposite side tacking mechanisms comprising a group of tack holders movable as a unit about an axis extending laterally of the last from tack-driving position to tack-receiving position.

95 44. In a machine of the class described, the combination with means for pulling an upper over a last, of tacking mechanisms for driving tacks at the toe end and at the opposite sides of the forepart of the last to fasten the upper, said tacking mechanisms comprising tack holders all movable from tack-driving position into positions in which they extend generally lengthwise of the last with their outlet ends directed upwardly to receive tacks, and automatic means for moving the tack holders between said different positions.

105 45. In a machine of the class described, the combination with means for pulling an upper over a last, of upper fastening mechanism comprising a group of tack holders mounted to move as a unit from positions to permit tacks to be driven in substantially horizontal directions into positions at a substantial angle to the line of drive with their outlet ends directed upwardly to receive tacks.

115 46. In a machine of the class described, the combination with means for pulling an upper over a last, of upper-fastening mechanism comprising a tack holder and a driver mov-

able together from tack-driving position to tip the outlet end of the tack holder upwardly to receive a tack.

47. In a machine of the class described, the combination with means for pulling an upper over a last, of upper-fastening mechanism comprising a tack holder and a driver movable together from tack-driving position into a position in which they extend generally lengthwise of the last with the outlet end of the tack holder directed upwardly to receive a tack.

48. In a machine of the class described, the combination with means for pulling an upper over a last, of upper-fastening mechanism comprising a tack holder and a driver movable together from tack-driving position into a position in which they extend substantially at right angles to the line of drive to receive a tack.

49. In a machine of the class described, the combination with means for pulling an upper over a last, of upper-fastening mechanism comprising a tack-holding nozzle and a driver therein movable together from tack-driving position to tip the outlet end of the nozzle upwardly to receive a tack, and means for delivering a tack to said nozzle through its outlet end.

50. In a machine of the class described, the combination with means for pulling an upper over a last, of upper-fastening mechanism comprising a group of tack holders and drivers movable as a unit from tack-driving position to tip the outlet ends of the tack holders upwardly to receive tacks.

51. In a machine of the class described, the combination with means for pulling an upper over a last, of upper-fastening mechanism comprising at each side of the forepart of the last a group of tack holders and drivers movable as a unit about an axis extending laterally of the last from tack-driving position to tack-receiving position.

52. In a machine of the class described, the combination with means for pulling an upper over a last, of upper-fastening means comprising a tack holder, a driver, and a driver bar movable lengthwise to operate said driver, said tack holder being movable relatively to the driver bar, in response to lengthwise movement of said bar, into and out of position to receive a tack.

53. In a machine of the class described, the combination with means for pulling an upper over a last, of upper-fastening means comprising a tack holder, a driver, and a driver bar movable lengthwise to operate said driver, said tack holder being mounted for tipping movement relatively to the driver bar between tack-driving position and tack-receiving position, and mechanism operative in response to lengthwise movement of said driver bar to impart said tipping movement to the tack holder.

54. In a machine of the class described, the combination with means for pulling an upper over a last, of upper-fastening means comprising a driver bar, a tack holder and a driver carried by said driver bar, said tack holder being mounted for tipping movement relatively to the driver bar between tack-driving position and tack-receiving position, and a member arranged to act on said tack holder to tip it between said different positions in response to movement of the driver bar.

55. In a machine of the class described, the combination with means for pulling an upper over a last, of upper-fastening means comprising a tack holder, a driver, and a driver bar movable lengthwise to operate said driver, said tack holder and driver being mounted for tipping movement together relatively to the driver bar into and out of position to receive a tack.

56. In a machine of the class described, the combination with means for pulling an upper over a last, of upper-fastening means comprising a tack holder, a driver, and a driver bar movable lengthwise to operate said driver, said tack holder and driver being mounted for tipping movement together relatively to the driver bar into and out of position to receive a tack, and mechanism operative in response to lengthwise movement of said driver bar to impart said tipping movement to the tack holder and driver.

57. In a machine of the class described, the combination with means for pulling an upper over a last, of upper-fastening means comprising a driver bar, a tack holder and a driver carried by said driver bar, said tack holder and driver being mounted for turning movement on the driver bar to tip the outlet end of the tack holder upwardly to receive a tack, and mechanism operative in response to retractive movement of the driver bar to impart said turning movement to the tack holder and driver.

58. In a machine of the class described, the combination with means for pulling an upper over a last, of upper-fastening means comprising a tack holder, a driver, a member supporting said tack holder and driver and movable to operate the driver, and a driver bar upon which said member is mounted for turning movement to present the tack holder in a position at an angle to the line of drive to receive a tack.

59. In a machine of the class described, the combination with means for pulling an upper over a last, of upper-fastening means comprising a tack holder, a driver, a member supporting said tack holder and driver and movable to operate the driver, a driver bar upon which said member is mounted for turning movement to tip the outlet end of the tack holder upwardly to receive a tack, and mechanism operative in response to movement of

said driver bar to impart to said member turning movements to present the tack holder alternately in tack-receiving and tack-driving positions.

5 60. In a machine of the class described, the combination with means for pulling an upper over a last, of upper-fastening means comprising a tack holder, a driver, a driver bar movable lengthwise to operate said driver, and means for tipping said tack holder relatively to the driver bar into and out of position to receive a tack.

15 61. In a machine of the class described, the combination with means for pulling an upper over a last, of upper-fastening means comprising a tack holder, a driver, a driver bar movable lengthwise to operate said driver, said tack holder being movable with the driver bar toward and from the shoe and mounted for tipping movement relatively to the driver bar into and out of position to receive a tack, and a member operative in response to lengthwise movement of the driver bar to impart said tipping movement to the 20 tack holder.

30 62. In a machine of the class described, the combination with means for pulling an upper over a last, of upper-fastening means comprising a tack holder, a driver, a driver bar movable lengthwise to operate said driver, said tack holder being movable with the driver bar toward and from the shoe and mounted for tipping movement relatively to the driver bar into and out of position to receive a tack, a member operative in response to lengthwise movement of the driver bar to impart said tipping movement to the 35 tack holder, and a spring controlling said member and permitting it to move with the driver bar in the tack-driving operation.

40 63. In a machine of the class described, the combination with means for pulling an upper over a last, of upper-fastening means comprising a group of tack holders and drivers, a driver bar movable lengthwise to operate said drivers, said group of tack holders being mounted for tipping movement as a unit relatively to the driver bar into and out of position to receive tacks, and mechanism operative in response to lengthwise movement 45 of the driver bar to impart said tipping movement to the tack holders.

50 64. In a machine of the class described, the combination with means for pulling an upper over a last, of upper-fastening means comprising a group of tack holders and drivers, a driver bar movable lengthwise to operate said drivers, said group of tack holders and drivers being mounted for tipping movement as a unit relatively to the driver bar into and out of position to receive tacks, and mechanism operative in response to 55 lengthwise movement of the driver bar to impart said tipping movement to the tack holders and drivers.

65. In a machine of the class described, the combination with means for pulling an upper over a last positioned with the bottom of its forepart substantially vertical and its toe pointing upwardly, of tacking mechanism arranged to drive a tack in a substantially horizontal direction to fasten the upper, said tacking mechanism comprising a tack holder mounted for tipping movement upwardly from tack-driving position to 70 present its outlet end in position to receive a tack delivered from above, and means for delivering a tack to the tack holder through its outlet end.

75 66. In a machine of the class described, the combination with means for pulling an upper over a last positioned with the bottom of its forepart substantially vertical and its toe pointing upwardly, of tacking mechanism arranged to drive a tack in a substantially horizontal direction to fasten the upper, said tacking mechanism comprising a tack holder movable from a substantially horizontal tack-driving position to a substantially vertical tack-receiving position, and means for delivering a tack to the tack holder through its outlet end when the tack holder is in tack-receiving position.

80 67. In a machine of the class described, the combination with means for pulling an upper over a last positioned with the bottom of its forepart substantially vertical and its toe pointing upwardly, of tacking mechanism arranged to drive a tack in a substantially horizontal direction to fasten the upper, said tacking mechanism comprising a tack holder mounted for movement from 85 tack-driving position into a position in which its outlet end is directed upwardly, means for delivering a tack to the tack holder through 90 its outlet end, and automatic means for moving the tack holder between said different positions.

95 68. In a machine of the class described, the combination with means for pulling an upper over a last positioned with its toe end pointing upward in a substantially vertical direction, of tacking mechanism arranged to drive a tack in a substantially horizontal direction to fasten the upper, said tacking mechanism comprising a tack holder mounted for angular movement about an axis extending laterally of the shoe to direct its outlet end upwardly in position to receive a tack delivered from above, and automatic means for imparting said movement to the tack holder.

100 69. In a machine of the class described, the combination with means for pulling an upper over a last positioned with its toe end pointing upward in a substantially vertical 105 direction, of tacking mechanism for driving a plurality of tacks to fasten the upper at the side of the forepart, said tacking mechanism comprising a group of tack holders movable as a unit from substantially horizon- 110

tal tack-driving position into position to direct their outlet ends upwardly to receive tacks delivered from above.

70. In a machine of the class described, the combination with means for pulling an upper over a last positioned with its toe end pointing upward in a substantially vertical direction, of tacking mechanism arranged to drive tacks at the toe end and at the opposite sides of the forepart of the last to fasten the upper, said tacking mechanism comprising a plurality of tack holders mounted for tipping movements upwardly from tack driving position to direct their outlet ends upwardly in position to receive tacks delivered from above.

71. In a machine of the class described, the combination with means for pulling an upper over a last positioned with its toe end pointing upward in a substantially vertical direction, of tacking mechanism arranged to drive tacks at the toe end and at the opposite sides of the forepart of the last to fasten the upper, said tacking mechanism comprising a plurality of tack holders mounted for tipping movements about axes extending laterally of the shoe from substantially horizontal tack-driving positions to substantially vertical tack-receiving positions, and means for delivering tacks to said tack holders through their outlet ends when the tack holders are in tack-receiving positions.

72. In a machine of the class described, the combination with means for pulling an upper over a last positioned with its toe end pointing upward in a substantially vertical direction, of tacking mechanism arranged to drive tacks at the toe end and at the opposite sides of the forepart of the last to fasten the upper, said tacking mechanism comprising a plurality of tack holders mounted for tipping movements about axes extending laterally of the shoe from substantially horizontal tack-driving positions into positions in which their outlet ends are directed upwardly to receive tacks, drivers cooperating with said tack holders, driver bars for operating said drivers, and means operative in response to movements of said driver bars to impart said tipping movements to the tack holders.

73. A machine of the class described having, in combination, a plurality of grippers for pulling an upper respectively at the toe end and at the opposite sides of the forepart of a last, and upper-fastening mechanism positioned between the opposite side grippers in a location opposite to the bottom of the last.

74. A machine of the class described having, in combination, a plurality of grippers for pulling an upper respectively at the toe end and at the opposite sides of the forepart of a last, said grippers extending heightwise of the last, and upper-fastening devices posi-

tioned at the inner sides of the respective grippers for driving fastenings at the toe end and at the sides of the forepart to fasten the upper.

75. A machine of the class described having, in combination, a plurality of grippers for pulling an upper respectively at the toe end and at the opposite sides of the forepart of a last, and upper-fastening mechanism permanently positioned in a location opposite to the bottom of the last for driving fastenings to fasten the upper.

76. A machine of the class described having, in combination, a plurality of grippers for pulling an upper respectively at the toe end and at the opposite sides of the forepart of a last, guiding means for said grippers constructed to prevent them from moving inwardly over the bottom of the last, and upper-fastening mechanism permanently positioned in a location opposite to the bottom of the last for driving fastenings to fasten the upper.

77. A machine of the class described having, in combination, grippers for pulling an upper over a last, means for engaging the tensioned upper on the lateral periphery of the last and for wiping it toward the edge of the last bottom, means for laying the margin of the upper inwardly over the bottom of the last, and upper-fastening mechanism permanently positioned in a location opposite to the bottom of the last for driving fastenings to fasten the upper.

78. A machine of the class described having, in combination, a plurality of grippers for pulling an upper respectively at the toe end and at the opposite sides of the forepart of a last, a plurality of wipers associated respectively with the different grippers for upwiping the upper, and upper-fastening mechanism positioned between the opposite side grippers for driving fastenings to fasten the upper.

79. A machine of the class described having, in combination, a plurality of grippers for pulling an upper respectively at the toe end and at the opposite sides of the forepart of a last, said grippers extending heightwise of the last, devices positioned at the outer sides of the respective grippers for upwiping the upper, and devices positioned at the inner sides of the respective grippers for fastening the upper.

80. A machine of the class described having, in combination, a plurality of grippers for pulling an upper respectively at the toe end and at the opposite sides of the forepart of a last, guiding means for said grippers constructed to prevent them from moving inwardly over the bottom of the last, a plurality of wipers associated respectively with the different grippers for upwiping the upper, and upper-fastening mechanism perma-

nently positioned in a location opposite to the bottom of the last for driving fastenings to fasten the upper.

81. In a machine of the class described, the combination with grippers for pulling an upper over a last, of a sole rest for supporting the last and a sole thereon against the pull of the grippers, said sole rest comprising different pairs of supporting members arranged to be positioned respectively in different locations lengthwise of the last, the members of each pair being constructed and arranged to overlap respectively the opposite side edges of the sole and being adjustable relatively to each other in directions widthwise of the last.

82. In a machine of the class described, the combination with grippers for pulling an upper over a last, of a sole rest for supporting the last and a sole thereon against the pull of the grippers, said sole rest comprising different pairs of supporting members arranged to be positioned respectively in different locations lengthwise of the last, the members of each pair being constructed and arranged to overlap respectively the opposite side edges of the sole and being adjustable relatively to each other in directions widthwise of the last, and the different pairs of members being relatively adjustable lengthwise of the last.

83. In a machine of the class described, the combination with grippers for pulling an upper over a last, of a sole rest for supporting the last and a sole thereon against the pull of the grippers, said sole rest comprising different pairs of supporting members arranged to be positioned respectively in different locations lengthwise of the last, the members of each pair being constructed and arranged to overlap respectively the opposite side edges of the sole and being adjustable relatively to each other in directions widthwise of the last, and a shaft extending lengthwise of the last, and having pinions thereon connected respectively to the different pairs of members for adjusting the members of each pair simultaneously in opposite directions, said shaft being adjustable lengthwise of the last, and means connecting one of the pairs of members to the shaft for movement lengthwise of the last with the shaft.

wise of the last and having pinions thereon connected respectively to the different pairs of members for adjusting the members of each pair simultaneously in opposite directions.

84. In a machine of the class described, the combination with grippers for pulling an upper over a last, of a sole rest for supporting the last and a sole thereon against the pull of the grippers, said sole rest comprising different pairs of supporting members arranged to be positioned respectively in different locations lengthwise of the last, the members of each pair being constructed and arranged to overlap respectively the opposite side edges of the sole and being adjustable relatively to each other in directions widthwise of the last.

85. In a machine of the class described, the combination with grippers for pulling an upper over a last, of a sole rest for supporting the last and a sole thereon against the pull of the grippers, said sole rest comprising different pairs of supporting members arranged to be positioned respectively in different locations lengthwise of the last, the members of each pair being constructed and arranged to overlap respectively the opposite side edges of the sole and being adjustable relatively to each other in directions widthwise of the last, a shaft extending lengthwise of the last and having pinions thereon connected respectively to the different pairs of members for adjusting the members of each pair simultaneously in opposite directions, said shaft being adjustable lengthwise of the last, and means connecting one of the pairs of members to the shaft for movement lengthwise of the last with the shaft.

In testimony whereof I have signed my name to this specification.

JOHN T. LANCASTER.
